UNITED STATES PATENT OFFICE.

CHARLES A. SCOTT, OF BOSTON, MASSACHUSETTS.

RAILWAY ELECTRIC SIGNAL APPARATUS.

SPECIFICATION forming part of Letters Patent No. 282,229, dated July 31, 1883.

Application filed June 18, 1883. (No model.)

To all whom it may concern:

Be it known that I, CHARLES A. SCOTT, a citizen of the United States, residing at Boston, county of Suffolk, State of Massachusetts, have invented or discovered a new and useful Improvement in Railway Electric Signal Apparatus; and I do hereby declare the following to be a full, clear, concise, and exact description thereof, reference being had to the accompanying drawings, making a part of this specification, in which—like letters indicating like parts—

Figure 1 is a view in elevation of an electric-circuit make-and-break mechanism, such as is adapted for use in connection with a railway-track for breaking a circuit by the action of a train when going in one direction—say from left to right—but which will not change the circuit under the action of a train going in the other direction. Fig. 2 is a like view of a similar apparatus, but constructed to operate in the reverse order as compared with that shown in Fig. 1—that is, to break the circuit under the action of a train going from right to left, and be inoperative under the action of a train going in the reverse direction. Fig. 4 illustrates a modification of Fig. 1, in that it operates only as a circuit-closer. Fig. 3 illustrates a like modification of Fig. 2.

In the following description I will designate these generally as "track-instruments," that being the name by which they are generally known in the art. B' will designate the track-instrument of Fig. 1, B² the track-instrument of Fig. 2, B⁴ the track-instrument of Fig. 4, and B³ the track-instrument of Fig. 3, it being understood that the parts of B⁴ and B³ not shown in Figs. 4 and 3 are to be made substantially as represented in Figs. 1 and 2, respectively.

Fig. 5 shows by diagram a train-actuated grade or street-crossing electric bell-ringing apparatus organized for operation on the open-circuit system, or with circuits operated by such track-instruments as are represented in Figs. 4 and 3; and Fig. 6 shows by a like diagram a similar apparatus organized for operation on the closed-circuit system, or with circuits operated by such track-instruments as are represented by Figs. 1 and 2, constructed as above stated.

My present invention relates to a system of

electric bell-ringing apparatus, particularly designed for use on a single-track road, or on a track on which trains are normally run both ways, and which is so arranged and organized, in connection with a street or railway grade crossing or station-house, or other point or place where an audible signal is desired, that a train approaching from either direction will close a bell-ringing circuit, which will remain closed until the train shall have reached the point or place to be protected, or shall have so nearly reached it that further alarm is unnecessary, and also so that such train, in leaving, shall not affect the circuit by which the same bell-ringing apparatus is operated by a train approaching from the opposite direction.

The track-instruments shown in Figs. 1 to 4 constitute, in their general features, the subject-matter of an application (Serial No. 92,960) already filed, and they are shown herein only to represent one suitable construction of devices adapted to the purposes in view; but in lieu of them, or any of them, other suitable form or construction of track-instrument adapted to do the same work under train action may be used, and all such are included herein as elements of the combinations hereinafter claimed, the same being designated generally as "track-instruments."

Referring first to Figs. 1 and 2 in general terms, b' b' may represent the level of the track-rails, and the posts a, pivoted at b, are suitably arranged to be moved by the car-wheels, so that a train going from left to right shall on Fig. 1 cause the arm a' to engage the lever c, tilt it on its pivoting-point in fulcrum-post d, so that its outer end shall move away from the spring-contact s and allow it to clear the other contact, s', and so break the circuit through wires r' r'. After the train passes, the springs c e bring the arm a' back to normal position, and a counter-weight, e', restores the broken connection. The same train, it will be seen, produces no effect as regards the contacts s s' of Fig. 2; but a train going from right to left on the same track will open the circuit through wires r r' of Fig. 2, in the manner above described, but will pass the track-instrument of Fig. 1 without affecting the circuit.

Going now to Fig. 5, R may represent a sin-

gle track, or a track on which trains are normally run in both directions, and the dotted lines R' may represent a grade street-crossing, or a station, railway grade crossing, or other point where protection is desired by the use of an audible signal, which here is represented by a bell-ringing apparatus, A, which may be of any suitable construction, preferably trembling or vibratory, and arranged at any convenient point, with suitable support and protection. A suitable track-instrument—say such as is shown in Fig. 4—is arranged at B⁴, and a corresponding instrument—say such a one as shown in Fig. 3—at B³. The bell-ringing circuit, which I will designate as "No. 1," includes the usual electro-magnet and battery, v, and is completed by the wires 1, 2, and 3, and armature-lever g. This armature is arranged so as to come within the influence of the electro-magnet D', so that when the electro-magnet is excited or charged it will be brought over to the contact-stops i i', and will receive a reverse motion by the usual retractile spring. At or near the crossing R', I arrange another track-instrument of any suitable construction, which in this case consists of a bar, n, arranged beside a track-rail, and in suitable position to be engaged by the car-wheels in passing, and thereby make electrical connection from the bar n to the rail. Wire 5 leads from the bar n to one pole of battery v', and wire 4 from the other battery-pole to the track-rail which is adjacent to the bar n, or to one which is electrically connected with such track-rail. These connections give me circuit No. 2. Wire 6 extends from one terminal of track-instrument B⁴ to wire 10, and thence by wire 11 to one pole of the electro-magnet D'; and wire 7 leads from the other terminal of track-instrument B⁴, and, branching, goes by wire 8 to armature-lever g, and by wire 9 to the wire 4, and through it is connected with one pole of battery v'. Wire 10 extends from one terminal of track-instrument B³ past its contact with wire 6 to contact-stop i', and a wire, 13, leads from the other terminal, B³, to one pole of battery v', and a wire, 12, from its other pole to electro-magnet D'.

It will now be seen that normally—that is, when no train is passing or present—the circuits will be open or broken at B⁴ and B³, and also at n, so that no closed circuit will exist to excite the magnet D', and so long as the latter is unexcited circuit No. 1 cannot be closed. A train approaching from the left will actuate track-instrument B⁴, so as to bring its terminals, Fig. 4, into contact, and thereby close a circuit by wires 7, 9, and 4 through battery v', and by wire 12 through electro-magnet D', and thence to wires 11 and 6 back to track-instrument B⁴. This I call "circuit No. 3." The magnet D' being thus excited, its armature-lever g will be drawn over to contact-stop i, and thereby circuit No. 1 will be closed and the bell-ringing apparatus will be put in operation, and will remain so until the train reaches the track-instrument n, and it

will be seen that the rebreaking of the circuit No. 3 at B⁴, which will take place as soon as the train shall have passed B⁴, will not operate to demagnetize the electro-magnet D', because the latter will be included in a closed circuit, No. 4, which will extend from battery v' by wires 4 9 8, armature-lever g, contact-stop i', wires 10 and 11, through magnet D', and by wire 12 back to the battery; but the practical efficiency of this circuit will be destroyed as soon as a train-wheel engages the bar n, for circuit No. 2 will thereby be closed, so as to take the current of battery v' and demagnetize magnet D'. The armature-lever g will then leave the contact-stops i i' and the bell-ringing circuit will be broken, so as to cause a cessation of the ringing of the bell, and the train then having passed the crossing further alarm is unnecessary. The entire apparatus is thus restored to normal position, and the outgoing train in passing track-instrument B³ will produce no effect, since that instrument is constructed to change the circuit only by a train going in the opposite direction. With a train going over the same track from right to left, the track-instrument B³ will be actuated so as to close the circuit No. 5 at that point, such circuit extending by wires 10 11 through magnet D', by wire 12 through battery v', and by wire 13 back to B³. The effect will be the same as before, both as to closing the bell-ringing circuit No. 1 and as to putting the magnet D' into a new circuit, No. 4, to keep it excited and the bell in operation until the train reaches the track-instrument n, and then the apparatus will be restored to normal position, as before, with a like cessation of bell-ringing, and a like non-action as the then outgoing train passes the track-instrument B³.

Going now to Fig. 6, the letters R R and n indicate the same as before; also, the bell-ringer A is the same, as well as circuit No. 1, the parts of which are indicated by the same letters, and I also make use of the same electro-magnet, D', and battery v'. The track-instrument of Fig. 1 is arranged at B¹ and the track-instrument of Fig. 2 at B². Wire 20 connects the terminals s' of the two track-instruments B¹ B². Wire 21 leads from the other terminal of track-instrument B¹ to one pole of battery v', wire 22 from its other pole to one terminal of electro-magnet D', and from its other terminal wire 23 leads direct to track-instrument n, and by a branch, 24, to the armature-lever g. The latter vibrates between two stops, i i', and when in contact with i closes circuit No. 1, and when in contact with i' closes the main circuit through wire 25 to the other track-instrument, B². Wire 26 connects the track-rail or other terminal of track-instrument n with one pole of battery v', as shown. Normally the armature-lever g will be on contact i', and then I have a closed main circuit from battery v', by wire 22, through electro-magnet D', by wires 23 24, armature-lever g, wire 25, track-instrument B², wire 20, track-instrument B¹, and wire 21, back to battery.

This will keep magnet D' excited, so as to hold armature-lever g to contact i^2 , and all other circuits will be broken, and No. 1 being broken, the bell will not ring.

5 Assume, now, that a train approaches from the left. At B' it will break the main circuit first described, and so release the armature-lever g , which, under the influence of its retractile spring, will go to contact i and close circuit No. 1 and set the bell to ringing. Though the terminals at B' will again come in contact as soon as the train passes, the main circuit will remain broken at i^2 until the train closes at n a circuit by wires 26, 23, and 22, through 15 electro-magnet D' and battery v'. This will restore the main circuit No. 1, so that the bell will cease ringing, and such main circuit will remain restored, since the magnet D', being excited, will hold its armature-lever g over to contact i^2 , and, as already stated, the departing train in passing over track-instrument B' will cause no electrical action at that point. With a train going the other way the same operations will take place, except that the 20 main circuit will be broken at B' instead of at B'; but the train in departing will cause no electrical action at B'.

The track-instruments B' B³ or B' B² may be located at any desired distance on either side 30 of the point to be protected—say one thousand five hundred or two thousand feet, more or less.

I claim herein as my invention—

1. The combination of a bell-ringing apparatus arranged at or in convenient proximity to the point to be protected, and included in a normally-broken local circuit, No. 1, an electro-magnet, D', for making and breaking such No. 1 local circuit, two circuit-changing 35 track-instruments arranged one in each direction therefrom and in connection with the same line of track, and both electrically connected with said electro-magnet D', and each adapted by the action of an incoming (but not 40 an outgoing) train thereon to close the bell-ringing local circuit, and an intermediate track-instrument arranged at or near the point to be protected, and an electric circuit therefrom by which, through train action at that

point, to break the said bell-ringing local circuit, substantially as set forth. 50

2. The combination of local circuit No. 1, including the electro-magnet of a bell-ringing apparatus, and composed in part of an armature-lever, g , an electro-magnet, D', arranged to operate said armature-lever, a train-actuated circuit-changing track-instrument to the left thereof and one to the right thereof, both in connection with the same line of track, and both electrically connected with said magnet D', and each adapted to change the electrical condition of said magnet only under the action of an incoming or approaching train, and a third intermediate track-instrument and an electric circuit therefrom, adapted, under train 60 action, to change the electrical condition of said magnet D', substantially as set forth. 65

3. The combination of a bell-ringing apparatus, an electric local circuit to operate the same, a make-and-break mechanism in such 70 circuit, an electro-magnet to operate such make-and-break mechanism, a train-actuated circuit-changing track-instrument to the right thereof and one to the left thereof, both electrically connected therewith and on the same 75 line of track, and each adapted to change the electrical condition thereof only under the action of an incoming or approaching train, and a third intermediate track-instrument and an electric circuit therefrom, adapted, under train 80 action, to reverse the electrical condition of said magnet from that given to it from either outer track-instrument, substantially as set forth. 85

4. In combination with a bell-ringer and the 85 normally-broken local circuit No. 1 thereof, an electro-magnet, D', included in normally-broken circuits, Nos. 3 and 5, such circuits including also the terminals of track-instruments B' B³; a shunt or side circuit, No. 4, and a restoring-circuit, No. 2, substantially as described with particular reference to Fig. 5.

In testimony whereof I have hereunto set my hand.

CHARLES A. SCOTT.
